EARTH LEAKAGE PROTECTION OF
APPARATUS AND MACHINES

Walter Bülow, Frankfort-on-the-Main, Germany,
assignor to Elektrizitäts-Aktien-Gesellschaft
vorm. W. Lahmeyer & Co., Frankfort-on-the-
Main, Germany, a German company

Application December 9, 1929, Serial No. 412,893
In Germany March 29, 1926

3 Claims. (Cl. 175—294)

My invention relates to protective appliances for electric plants.

It is an object of my invention to provide a protective appliance for a plant with a power 5 transformer intermediate a system and an electric apparatus, for instance, a generator.

To this end, I provide a voltage transformer which is connected to the zero point of the apparatus or generator and to earth, and has a 10 relay in its secondary circuit. The relay which may be of the amperemetric or wattmetric type, has its coil (or, in the case of a wattmetric relay, its voltage coil) shunted by a ballast resistor which is directly connected in parallel to the 15 secondary of the voltage transformer.

Ballast or Nernst resistors are old in the art and consist of a pure iron wire suspended in hydrogen gas.

It has already been proposed in plants in which 20 the apparatus to be protected operates directly on the system, and not on an intermediate power transformer, to provide an earthed voltage transformer with a relay and a ballast resistor in the secondary circuit of the voltage transformer.

This ballast resistor, however, is connected in 25 series to the coil of the relay, and not in shunt as in the present invention.

Conditions in a plant without an intermediate power transformer are quite different from those 30 in a plant with such a transformer, to which the present invention relates.

In plants without a power transformer the leakage current is always sufficient for operating a safety appliance while in plants with a power 35 transformer the capacity of the phases to earth is so small that it is necessary first and foremost to generate a leakage current of the required intensity. The leakage current was generated heretofore in a voltage transformer in combination 40 with an invariable resistor.

According to my invention the invariable resistor is replaced by a ballast resistor arranged as described. I may combine a shunting ballast resistor with the series ballast resistor referred 45 to above, but my invention resides in providing the shunting ballast resistor.

In the accompanying drawing Figure 1 is a curve showing the relation between the current and the terminal voltage in ballast resistors; 50 Figs. 2, 3 and 4 are diagrams of connections which may be employed according to my invention.

The diagram illustrated in Fig. 1 in which current is plotted against voltage shows the well known property of ballast resistors, i. e. that the 55 current flowing through the resistor rises at first

rapidly with the increase of the terminal voltage but afterwards remains nearly constant although the terminal voltage is further increased. By providing a ballast resistance which shunts the coil, or a coil, of the relay, the earth leakage current will be limited approximately to the value which is required for the operation of the relay. This arrangement has the great advantage that burning which for instance takes place in case of an earth leakage within a generator is greatly 60 limited. In many cases it is possible to continue to work for hours with the defective machine or with the apparatus exposed to earth leakage without increase in the burning. It has been found that the earth leakage current should be 65 limited to about 5 amps., as against the usual intensity of about 20 amps. By the shunting ballast resistor according to my invention the earth leakage current is limited to about $\frac{1}{5}$ of this amount and burning in the machine to be protected by my appliance is prevented or does not spread. In such a case with any organic insulating materials the layer of carbon produced by the action of the voltaic arc is sufficient to 70 discharge the earth leakage current.

A plant with an amperemetric relay in the secondary circuit of the voltage transformer and a ballast resistor shunting the coil of the relay, is illustrated in Fig. 2 where T is the power transformer and G is an apparatus, such as a 85 generator, which is connected through the power transformer T to high voltage system N. S is a voltage transformer which is connected to the zero point of the apparatus or generator G and to earth, and R is an amperemetric relay with 90 its coil in the secondary circuit of voltage transformer S. B is a ballast resistor which shunts the coil of relay R and is directly connected in parallel to the secondary of the voltage transformer S. L is another ballast resistor which 95

is connected to the secondary in series and may, or may not, be provided. The resistors B and L are so designed that the earth leakage current will be limited approximately to the value which corresponds to the operating current of the 100 amperemetric relay R and never exceeds 5 amperes. Obviously instead of using individual ballast resistances B or L for instance I may subdivide these resistors into a plurality of resistors of equal action and even form groups of those 105 partial resistors connected together without departing from the gist of the invention. With a ballast resistor, or resistors, according to my invention it is always possible to fulfill the condition that the equivalent resistance in place of 110

the primary side of the voltage transformer S becomes small in the case of an earth leakage on the high voltage side of the power transformer T, but becomes large in the case of an 5 earth leakage on the low voltage side of the power transformer T or on the generator side.

The arrangement according to the diagram shown in Fig. 2 is preferably employed if the machines or apparatus to be protected work on a system N of comparatively small extension. If the said machines and apparatus work on a system of a large extension it is only necessary to replace the amperemetric relay R by a wattmetric relay R' as shown in Figs. 3 and 4 having 15 two co-operating exciting windings or coils one of which is the voltage coil whilst the other is the current coil.

Figs. 3 and 4 show that the voltage coil of the wattmetric relay R' is connected to the secondary 20 of transformer S in the same manner as the single coil of the amperemetric relay R in the arrangement illustrated in Fig. 2, and shunted by the ballast resistor B. L is the series ballast resistor.

25 According to Fig. 3 the current coil of the wattmetric relay R' is connected to the secondary side W of a so called integrating current transformer E the iron core of which is indicated in dotted lines. The current flowing through W corresponds to the sum of the currents which 30 flow to or from the generator G.

Instead of using one special transformer E integrating the currents which flow to or from the generator G standard current transformers 35 the secondary windings of which are connected in parallel may also be used as illustrated in Fig. 4 showing four standard current transformers E₁, E₂, E₃ and E₄ with paralleled secondary windings W₁, W₂, W₃ and W₄ respectively. The current coil of the wattmetric relay 40 R' is connected to these windings. The voltage coil of this relay is shunted by the invariable resistance X so that the terminal voltage is de-

termined by the current flowing through X in consequence whereof the said terminal voltage is maintained throughout its full value independent of the voltage between the neutral or zero point of the generator G and earth.

I claim:

1. In an electric plant, an electric apparatus, a system, a power transformer intermediate said system and said apparatus, and a protective appliance including: a voltage transformer connected to the zero point of said apparatus and to earth, a relay in the secondary circuit of said voltage transformer, a coil in said relay, a ballast resistor connected in parallel to said coil and directly connected in parallel to the secondary of said voltage transformer, and another ballast resistor in series with said coil.

2. In an electric plant, an electric apparatus, a system, a power transformer intermediate said system and said apparatus, and a protective appliance including: a voltage transformer connected to the zero point of said apparatus and to earth, a wattmetric relay in the secondary circuit of said voltage transformer, a voltage coil in said relay, a ballast resistor connected in parallel to said coil and directly connected in parallel to the secondary of said voltage transformer, and another ballast resistor in series with said coil.

3. In an electric plant, an electric apparatus, a system, a power transformer intermediate said system and said apparatus, and a protective appliance including: a voltage transformer connected to the zero point of said apparatus and to earth, a wattmetric relay in the secondary circuit of said voltage transformer, a voltage coil in said relay, a ballast resistor connected in parallel to said coil and directly connected in parallel to the secondary of said voltage transformer, another ballast resistor in series with said coil, and an invariable resistance connected in parallel to said voltage coil.
